To all whom it may concern:

Be it known that we, Albert S. Root and Jacob Levin, citizens of the United States, residing, respectively, at Miami, in the county of Dade and State of Florida, and Brooklyn, in the county of Kings and State of New York, have invented a new, original, and ornamental Design for a Corner Store Front, of which the following is a specification, reference being had to the accompanying drawings, forming part thereof.

Figure 1 is a perspective view of a corner store front showing our new design.

Figure 2 is a top plan view of our new design. The two shaded panels connecting the three uprights have a substantially smooth surface as has the shaded portion at the bottom.

The stippling represents a rough surface in which are embedded cocoanut shells.

JACOB LEVIN.
